CLAIM

The ornamental design for a attachable writing surface
for use in an automobile, as shown and described.

DESCRIPTION

FIG. 1 is a perspective view of an attachable writing
surface for use in an automobile showing my new de-
sign;

FIG. 2 is a side elevational view, the opposite side being
a mirror image thereof;

FIG. 3 is a top plan view; and,

FIG. 4 is a bottom plan view thereof.

FIG. 1

FIG. 2

FIG. 3

FIG. 4
